Primary Examiner—Alan P. Douglas**Assistant Examiner—Antoine D. Davis****Attorney, Agent, or Firm—Cumpston & Shaw****[57] CLAIM**

The ornamental design for an automatic capsule mixing device, as shown and described.

DESCRIPTION

FIG. 1 is a front perspective view of an automatic capsule mixing device showing my new design;
FIG. 2 is a top plan view thereof;
FIG. 3 is a left side elevational view thereof;
FIG. 4 is a front elevational view thereof;
FIG. 5 is a bottom plan view thereof;
FIG. 6 is a right side elevational view thereof; and,
FIG. 7 is a back elevational view thereof.

FIG. 2

FIG. 4

FIG. 1

FIG. 3

FIG. 7

FIG. 5

FIG. 6
